UNITED STATES PATENT OFFICE.

ALBERT B. CULVER, OF AGUASCALIENTES, MEXICO

CIRCUIT-CLOSER.

No. 911,943.

Specification of Letters Patent.

Patented Feb. 9, 1909.

Application filed August 24, 1908. Serial No. 449,931.

To all whom it may concern:

Be it known that I, ALBERT B. CULVER, citizen of the United States, residing at Aguascalientes, Mexico, have invented certain new and useful Improvements in Circuit-Closers, of which the following is a specification.

This invention relates to circuit closers or timers for internal combustion engines, and particularly to that class thereof in which the contact is made by means of a ball running over a contact terminal or plate.

An object of the invention is to improve the means for carrying the ball which makes the contact.

A further object of the invention is to provide means for cleaning the surface of the terminal so that a perfect contact will be afforded.

With these and other objects in view, the invention is hereinafter described and is illustrated in the accompanying drawings, in which—

Figure 1 is a longitudinal section of the device. Fig. 2 is a cross section. Fig. 3 is a cross section of a modification.

Referring specifically to the drawings, 6 indicates a ring of fiber or other insulating material supported by a metal back 7 which 30 has a cuff 8 fitting over a bushing 9 on the shaft 10 which is preferably the cam or valve operating shaft of the engine. A removable metal front 11 is secured to the fiber ring, which is also provided at suitable distances 35 apart with brass contact plates or terminals 12 which will be provided with connections to the coil. At each edge, on its internal surface, the fiber ring is rabbeted as at 13, forming a groove for the reception of waste 40 or sediment swept from the ring. The inner surface of the ring is concentric with the shaft.

The end of the shaft within the ring carries a head 14 formed with a radially extending tube 15 which receives a cartridge or holder consisting of a tube 16 in which is fitted a disk 17. The inner tube or cartridge holds the hardened steel ball 18 in its outer end, in position to run over the inner 50 surface of the ring 6 and to close the circuit on reaching the terminals 12. This ball rests against a series of balls 19 held in a ball race 20 in the disk 17, forming ball bearings which prevent friction. The cartridge is pressed behind by a coiled spring 21

contained within the tube and pressing against the disk 17.

At a position diametrically opposite to the contact ball, the head carries a metal blade or cleaner 22 with a threaded stem 23 which screws into a fiber bushing 24 set in a socket in the head. The purpose and function of this cleaner is to act as a brush to sweep any dirt or deposits from the face of the contact terminals 12 and to also clear 60 the track of the ball around the fiber disk. The cleaner is adjustable, and it may be set in contact with the track if desired, but I have found that this is unnecessary, and that by setting it at a slight distance, say 1/64 65 of an inch from the track, it performs its function, and will clear or clean the contact points as much as is necessary. Any waste oil or sediment which might otherwise collect on the track is by the action of the described device swept laterally into the 70 grooves at 13, and will remain there.

Instead of the blade 22, a brush, such as shown at 25 in Fig. 3, may be used, consisting of a bunch of wires set in an insulating 80 bushing 26.

The cartridge carrying the contact ball has a working fit in the tube 15, and in consequence of the spring 21 the ball is held against the track and closes the circuit on 85 passing over the terminals 12. The ball bearings afforded by the balls 19 prevent friction to a great extent and at the same time give a good circuit connection. Obviously the number of terminals 12 will be 90 varied according to the number of cylinders in the engine, one side of the circuit, as usual, being grounded to the shaft 10. The cleaning device obviates an objection heretofore found to exist, due to the collection of 95 dirt or waste oil on the terminals, thereby preventing the closing of the circuit.

I claim:

1. In a circuit closer, the combination of a ring having contact terminals therein, a contact device rotatable in the ring and across the terminals, and an insulated metallic cleaner rotatable in the ring with said device and passing close to the terminals but out of contact therewith, to dislodge foreign 105 matter therefrom.

2. In a circuit closer, the combination of a ring having contact terminals therein, and a rotary contact device in the ring, having a ball which runs around the ring and across 110

the terminals, and anti-friction bearings in which said ball is mounted.

3. In a circuit closer, the combination of a ring having contact terminals therein, a shaft extending into the ring and provided with a head having a tube projecting toward the ring, a holder in said tube, having ball bearings therein, and a ball held by the holder and resting against said bearings and

arranged to roll around the ring and across 10 said terminals.

In testimony whereof, I affix my signature in presence of two witnesses.

ALBERT B. CULVER.
